MEANS OF ELIMINATING INTERFERENCE
CAUSED BY INDUCTION IN ELECTRON
TUBES

In Germany August 8, 1936

3 Claims. (Cl. 250—27)

This invention relates to screens for means of eliminating interference caused by induction in electron tubes, and leads coming to and from such tubes. In particular this invention relates to the elimination of interference in tubes in which the leads are brought in through a plurality of projections.

Examples of such tubes are picture transmitting tubes for television purposes with built-in electron multiplier systems in which an optical image is focused upon a photosensitive cathode. The electrons liberated from the photo-cathode are focused in image relation by electrical or magnetic means in a plane in which a scanning aperture of the size of a picture element is disposed which allows the electrons constituting the signal corresponding to one picture element to fall upon a target or into an electron multiplier system. Variable magnetic transverse fields have the effect that electrons from all picture elements come to an electron collector in a successive order.

The varying magnetic fields inductively affect the collector and the leads to the electron multiplier system. Especially when an electron multiplier system is employed which necessitates a number of potential leads, these interferences may become so great that the television image becomes flat or is entirely covered by interference noise.

According to the invention shielding means are provided, particularly inner and outer screens, whereby the inner screen is connected with the outer screens located at every projection which contains leads to be screened. The outer screens leading from the projection are connected only to the inner screen and both are isolated from ground. Only in such an arrangement complete elimination of interference is achieved, whereas for instance the earthing of the exterior screen in one or several places does not render the desired result. The described manner of interference is possible in all kinds of magnetic interfering fields. Not only the deflecting fields but also, for instance, alternating fields created by power mains are often the cause of interference, and their detrimental effect may be eliminated in the described method.

Fig. 1 shows a schematic diagram, partially in section, of an image dissector tube connected to an amplifier and a voltage divider.

Fig. 2 shows a schematic sectional diagram of a modification of the invention, wherein a T-shaped shielding element is provided.

Fig. 3 shows a modification of the means for grounding the inner shielding devices.

The picture analyzer tube 1 of Fig. 1 contains a photosensitive cathode 2 and an anode 3, whereas the deflecting coils 4 are disposed outside 5 of the tube. The magnetic fields of these coils which are necessary for deflection have an interfering effect upon the leads to the signal electrode and to the electron multiplier in the tube. The signal electrode not shown in the drawings 10 lies behind the scanning aperture 5 of a screening cylinder 6. The lead 7, which is connected to the signal electrode (not shown), is brought out through an extended seal 8 on one side of the tube, to an amplifier. Outside of the tube the 15 lead is screened by a cylinder 9 which is directly connected with a cylinder 6 through the glass wall and protrudes over the cylinder 6. The screen 9 of the signal lead is connected with the screening case 40 of the amplifier, the first tube 20 10 of which is schematically indicated. The cathode of the tube 10 is connected to the case 40 at a point 11.

On the other side of the tube are, for instance, three voltage leads 12, 13, and 14, which are connected to the electron multiplier, not shown on the drawings, and which are brought in through an extrusion 15. The leads are screened off by the cylinder 16, which is connected to the inner cylinder 6 through a second sealed-in lead 17. 25 The cylinder 16 is connected to a case 18 in which the voltage leads 12, 13 and 14 are connected to the case through the condensers 19, 20, 21. The leads are connected through the resistances 22, 23 and 24 to a voltage divider, which may be 30 grounded in some suitable manner, whereas all other screening parts must be isolated. A ground connection on any other spot, for instance, on the cylinders 9 or 16, leads to heavy interferences. If the amplifier 10 is a pre- 35 amplifier, the connections of which with the main amplifier must also be screened, it is advisable to use the circuit shown in Fig. 1. The plate and filament voltage is brought in through a screened cable 41. Parallel and in close proximity a second screen cable 42 is disposed which contains the modulation lead. The plate and filament voltage leads are connected with the case 40 through the condensers 38 and 39. The case of the main amplifier is grounded at 43 whereas all 45 other screens are isolated.

As many voltage leads as desirable may be brought into the electron multiplier if they are connected by means of condensers to the casing as shown in the drawing because the signal elec- 50 55

trode is separately brought out from the tube. It is also possible to bring out the leads through more than two projections. In this case lead-ins are provided for the inner screening at every projection. Fig. 2 shows a cross-section through a picture analyzing tube whereby this cross section shows an arrangement with three projections. The inner screen has the form of a T-shaped case 25. The outer screens 26, 27 and 28 are connected with the inner screen 25 through the sealed-in leads 29, 30 and 31 and are not permitted to touch each other outside of the tube. The signal electrode is brought out through one arm of the T-shaped case, whereas the voltage leads 32, 33, 34 and 35 go through the two other arms. The connection of these leads to the screen by means of condensers is made in the same manner as shown in Fig. 1. The four voltage leads go to the same potentiometer 36 which may be connected to ground as may seem suitable.

In some cases it may be advisable to connect the entire screening system in the interior of the tube through a capacity 37 to the outer screen which is connected to ground and to apply by way of a resistance a voltage to the end of the other branch of the outer screening. The condenser 37 may be shunted by a resistor 37' as is shown in Fig. 3.

The arrangement is not limited to the picture analyzing tubes shown in the drawings. This

invention may be applied in all cases of high frequency work where inductive interferences are to be eliminated and where it is to be prevented that screens should form a loop in a magnetic field.

We claim:

1. In combination with a television transmitting tube, means for shielding signal carrying leads from potential carrying leads comprising a plurality of extruded portions formed on said tube, potential leads and signal leads disposed separately through said extrusions and sealed therein, inner shielding means surrounding said leads and extending into said extruded portions of said tube, external shielding members individually associated with said signal and potential carrying leads, and means for connecting each of said external shielding means separately to said internal shielding means and means for grounding said external shielding means.

2. The combination of a television transmitting tube and a shielding device substantially as described in claim 1, wherein said signal and potential leads are capacitatively connected to said external shielding means.

3. A device substantially as described in claim 1, wherein said potential leads are connected to a voltage dividing device, said voltage dividing device being grounded.

WALTER BÜNGER.
